UNITED STATES PATENT OFFICE.

MORTON MURPHY, OF JANEVILLE, WISCONSIN.

AUTOMATIC CUT-OFF.

1,248,889.

Specification of Letters Patent. Patented Dec. 4, 1917.

Application filed April 15, 1916. Serial No. 91,471.

To all whom it may concern:

Be it known that I, MORTON MURPHY, a citizen of the United States of America, residing at Janesville, in the county of Rock and State of Wisconsin, have invented certain new and useful Improvements in Automatic Cut-Offs, of which the following is a specification, reference being had therein to the accompanying drawing.

10 This invention relates to an automatic shut-off for automatically cutting off the electrical current of a fireless cooker when a given amount of fluid has been vaporized from the well of the cooker.

15 Another object of this invention is the production of a simple and efficient means for normally closing the electrical circuit to permit the heating means to be operated, whereby the circuit closing mechanism will 20 be automatically and efficiently opened when a given amount of fluid is vaporized from the well of the cooker.

With these and other objects in view this invention consists of certain novel combinations, constructions, and arrangements of parts as will be hereinafter fully described and claimed.

In the accompanying drawings:

Figure 1 is a top plan view of the fireless 30 cooker.

Fig. 2 is a side elevation of a portion of the body of the cooker.

Fig. 3 is a top plan view of the automatic cut-off mechanism, the cover being removed 35 therefrom.

Fig. 4 is a central longitudinal section taken on line 4—4, of Fig. 3.

Fig. 5 is a longitudinal section through the circuit breaker.

40 Fig. 6 is a section taken on line 6—6, of Fig. 1.

Fig. 7 is a section taken on line 7—7, of Fig. 4.

Fig. 8 is a section taken on line 8—8, of 45 Fig. 5.

Fig. 9 is a detail perspective of one of the clamping brackets for holding one end of the circuit breaker.

Fig. 10 is a detail perspective of the tripping bracket.

Fig. 11 is a detail perspective of one of the pivot plates for supporting the circuit breaker and tripping bracket.

Fig. 12 is a diagrammatic view showing 55 the electrical circuits involved for operating

the heating element within the fireless cooker as is set forth in my co-pending application Serial Number 91,472, filed April 15, 1916, relating to a heating element.

By referring to the drawings it will be 60 seen that 1 designates the body of the cooker which is provided with a heating mechanism placed therein of suitable construction. This heating element 2 is provided with a plurality of terminals 3, to one of which terminal 3 is electrically connected the electrical supply wire 4, and the other terminal 3 is connected to a wire 5 which is in turn connected to an automatic switch 6 indicated in the diagram in Fig. 12. A contact 7 is employed adjacent the switch 6 and it is adapted to complete the circuit through the heating element 2, and this contact point 7 is connected to the wire 4' which constitutes a return wire for the electrical supply. The 70 automatic switch is merely indicated by the reference numeral 6 in the diagram in Fig. 12 to facilitate the description of the electrical circuits involved.

The body of the cooker 1 is provided with 80 the usual cover 8, and this cover 8 is provided with a valve casing 9 upon the top thereof having a projecting sleeve 10, within which projecting sleeve 10 extends the nozzle 11 of the steam condenser 12. This steam 85 condenser 12 comprises an elongated tubular body having a discharge or drain aperture 13 near the outer end thereof, and the lower end of this steam condenser 12 is fitted within the pocket 14 of the cover 15 carried by 90 the circuit breaking housing 16 as will be hereinafter more clearly described. It should be understood that this tube 11 is detachable from the tube 10 so as to permit the device to be attached to the cooker when so desired, and also to permit the same to be removed for the purpose of cleaning and the like.

The housing 16 comprises a body having laterally extending ears 17, which ears are 100 securely fastened to the top of the cover 8 of the fireless cooker. The body 16 is also provided with longitudinally extending channels 18 upon the top thereof, which channels permit the passage of the conducting wires 19 therethrough and permit the cover 15 to fit snugly and tightly over the upper edges of the body 16 as is illustrated in Fig. 6 of the drawings.

A tripping bracket 20 is mounted within 110

the casing 16 and is provided with depending tapering ears 21 upon each side thereof, thereby producing a V-shaped notch 22 between the ears 21. This notch 22 is adapted 5 to fit over the notch 23 formed in the lower section 24 of the support as illustrated clearly in Fig. 6. This lower section 24 of the support comprises a thin sheet metal body having its side edges fitting within the 10 vertically extending channels 25 of the body 16 as clearly illustrated in Figs. 3 and 7. An upper section 26 is fitted over the lower section 24 of the support and is adapted to fit snugly within the slots 25 and is provided 15 with a substantially V-shaped upper face 27. The cover 15 of the housing 16 is adapted to firmly hold the upper section 26 upon the upper edge of the lower section 24, and thereby prevent the support from working 20 loose. It will, therefore, be seen that since the body of the tripping bracket 20 fits within the notch 23 of the lower section 24, the upward movement of the bracket 20 is limited or prevented by means of the 25 upper section 26 of the support. This structure is illustrated clearly in Fig. 6. The body of the tripping bracket 20 is provided with a rearwardly extending ear 28, which rearwardly extending ear 28 supports a drip 30. The forward end of the tripping bracket 20 is substantially Z-shaped and is provided with a forwardly extending tripping end 30, which forwardly extending tripping end 30 engages the upwardly extending 35 lip 31 of the inclined arm 32 of the circuit breaker 33. This circuit breaker 33 comprises a metallic bracket having depending tapering ears 34 similar to the ears 21 of the bracket 20, thereby producing a 40 substantially V-shaped notch 35 for constituting a pivot for fitting over the lower section 24' of the supporting bracket clearly illustrated in Fig. 4 of the drawings, as well as Fig. 7. This lower section 24' fits 45 in notches 25 formed similar to the notches referred to in connection with the support for the tripping bracket 20, and the upper section 26' of the support for the circuit breaker is of similar construction to the 50 upper section 26 of the support for the tripping bracket 20.

A supporting clip 36 is supported upon each end of the body 33, and each clip comprises a pair of spring jaws 37, between 55 which spring jaws 37 are adapted to fit the metallic ends 38 of the circuit breaking tube 39. Each jaw 37 is provided with an inwardly bent ear 40, which inwardly bent ear 40 constitutes means for limiting the 60 longitudinal movement of the circuit breaking tube 39 within the brackets or clips 36. The circuit breaking tube 39 is preferably formed of glass having its ends fitting within the metallic ends or caps 38, and this 65 tube 39 is provided with an upwardly pro-

jecting finger 41 to permit the tube to be gaged at a proper level. The tube 39 is provided with an insulating rod 42 arranged centrally thereof, and this insulating rod 42 engages at each end the conducting wires 70 43 and 44, these conducting wires 43 and 44 being grounded upon the caps 38. It will, therefore, be seen that the clips 36 will form an electrical contact with the respective caps 38. One of the clips 36 is electrically connected to the wire 19 by means of a conducting wire 45, and the other wire 19' is electrically connected to the opposite clip 36 by means of a conducting wire 46 as 75 clearly illustrated in Fig. 3. It will, therefore, be seen that as long as the circuit breaking tube 39 remains in a horizontal position, the current will pass through the mercury bubble 47 between the conducting wires 43 and 44 and allow an electrical circuit to be maintained through the wire 19, through the wire 45, through one of the clips 36, through one of the caps 38 to the conducting wire 44, through the mercury bubble 47, through the conducting wire 43 80 out through the other clip 36 out through the wire 46 and return through the wire 19'. 85

A rod 48 is mounted within a vertically extending plate 49 formed in the inner face of the casing 16 and is provided with an inturned lower end 50 and an outturned upper end 51. This rod 48 is rotatable within the bracket 52 which supports the same, and as the upper end 51 is swung toward the letters "On" printed upon the 95 top 15 as shown in Fig. 1, and the rod is lifted, the end 50 will fit under the body 33 and lift one end of the body 33 to a horizontal position and allow the forwardly projecting end 30 of the tripping bracket 20 to 100 fit under the upturned end 31 of the body 33 as clearly illustrated in Fig. 5 of the drawings, thereby holding the body 33 in a horizontal position and holding the circuit breaking tube 39 in a horizontal position to 110 permit an electrical current to pass therethrough.

In the operation above described the circuit closing or breaking mechanism is in an operative position. The circuit is broken as 115 follows:

When steam is generated within the well of the fireless cooker and passes up through the tube 11, this steam will pass into the condenser casing 12 and will thereby be condensed and drained through the draining aperture 13 into the pocket 14 and be discharged through the aperture 14' upon the pan 29. As soon as sufficient moisture or liquid has entered the pan 29, the pan will 120 be forced downwardly, thereby removing the projecting end 30 out of engagement with the upwardly extending end 31 of the circuit breaking body 33 and cause the inner end of the body to swing downwardly 125 130

and thereby cause the mercury bubble 47 to move toward one end of the circuit breaking tube 39, thereby breaking the circuit between the contact wires 43 and 44. It should be understood that the casing 33 is so balanced as to have the heaviest end upon the inner end of the casing 33, and cause the same to automatically drop downwardly as soon as the tripping bracket 20 is released therefrom.

From the foregoing description it will be seen that a very simple and efficient structure has been produced for permitting an electrical circuit to be readily and easily broken as the heat within the well of the fireless cooker reaches a degree sufficient to evaporate a given amount of fluid, and it should be further understood that the automatic cut-off is a very simple and efficient construction and may be manufactured at a minimum cost.

Having thus described the invention what is claimed as new, is:—

1. An automatic cut-off for a fireless cooker comprising a casing, a condenser, a connection between the interior of the cooker and the condenser for transferring and collecting the vapors from the cooker, and means coöperating with said condenser for automatically cutting off an electrical current passing through said automatic cut-off when a predetermined amount of moisture has been discharged from said condenser.

2. An automatic cut-off for a fireless cooker comprising a casing, a condenser, a connection between the interior of the cooker and the condenser for transferring and collecting the vapors from the cooker, an automatic circuit breaker coöperating with said condenser and adapted to be swung to an inoperative position when a predetermined amount of moisture has been discharged from said condenser.

3. An automatic shut-off of the class described comprising a cooker having a casing, 45 a condenser, a connection between the interior of the cooker and the condenser for transferring and collecting the vapors from the cooker, an automatic circuit breaker, a tripping bracket, and means carried by said 50 tripping bracket and adapted to receive moisture from said condenser for automatically throwing said circuit breaker to an inoperative position when a predetermined amount of moisture has been deposited upon 55 said tripping bracket.

4. An automatic shut-off for a fireless cooker comprising a casing, a condenser, means for facilitating the admission of steam into said condenser, an automatic circuit breaker pivotally mounted within said casing, a tripping bracket engaging said circuit breaker, said tripping bracket provided with a pan at one end, said condenser being adapted to discharge moisture into 65 said pan for tripping said tripping bracket and releasing the same from said automatic circuit breaker whereby said automatic circuit breaker will be caused to drop to an inoperative position.

5. In combination with a cooker, of an automatic shut-off, said cooker provided with a casing, a condenser, a connection between the interior of the cooker and the condenser for transferring and collecting the vapors 75 from the cooker, a heating medium positioned within said cooker, and said automatic shut-off adapted to automatically shut-off the heat from said cooker when a predetermined amount of moisture is deposited in said condenser.

In testimony whereof I hereunto affix my signature.

MORTON MURPHY.
